UNITED STATES PATENT OFFICE.

WILLIAM F. DATHAN, OF GLENCOE, ILLINOIS.

TOY VEHICLE.

Application filed June 4, 1924. Serial No. 717,836.

To all whom it may concern:

Be it known that I, WILLIAM F. DATHAN, a citizen of the United States, residing at Glencoe, in the county of Cook and State of Illinois, have invented a certain new and useful Improvement in Toy Vehicles, of which the following is a specification.

My invention relates to toy vehicles of the wheeled type that are adapted to be propelled either by direct contact of the occupant's feet with the ground or by suitable gearing such, for example, as a chain and sprocket mechanism, and my object is to improve generally the construction of such vehicles to render them particularly attractive to children and to enhance their strength and durability.

The vehicle of my invention consists essentially of a body and supporting wheels, one of which latter is angularly movable with respect to the direction of travel of the vehicle for steering purposes, and it is my more specific object to provide an improved connection between the body and the steering wheel whereby the body, which is adapted to be shaped to resemble an object such as a horse, dog or other animal, may be formed of relatively thin, vertically disposed material and attached, regardless of its shape, to the steering wheel by the same connecting means.

Also it is my object to provide a simple, cheap and efficient means of bracing the body and in instances where the propelling means consists of a chain and sprocket mechanism, of tightening the chain of such mechanism.

With the foregoing and other objects in view, my invention consists in the novel features of construction, combination and arrangement of parts, as will be hereinafter more fully described, illustrated in the accompanying drawings and defined in the appended claims.

45 In the drawings, wherein like characters of reference denote corresponding parts in the different views

Figure 1 is a side elevation of a toy vehicle embodying the novel and essential features of my invention;

Figure 2, a front elevation;

Figure 3, a rear elevation;

Figure 4, a detail perspective showing the parts of the connecting means between the body and the steering wheel separated; and

Figure 5, a detail view illustrating the construction of the connecting means between the body and the steering wheel which adapts the connection for attachment to bodies of different shapes.

Referring to the drawings in detail, 10 designates the body of my improved vehicle, 11 the front steering wheel thereof and 12, 12 the rear supporting wheels.

The body 10 is cut from a board or other piece of material to resemble in outline an object such as a horse, dog or other animal, and at suitable points upon opposite sides of the same are secured the upper end portions of suitably braced downwardly and outwardly extending arms 13, 13 that are connected in any suitable manner at their lower ends to bearing housings 14, 14 within which is journaled a shaft 15 that connects the rear wheels 12, 12 whereby the body is supported from said wheels.

On the shaft 15 is secured a sprocket 16 and to the lower edge of the body 10 is secured a bracket 17 carrying a pedal and sprocket mechanism 18, the sprocket of which is connected to sprocket 16 by a chain 19, a propelling mechanism thus being provided that is of conventional and well known type. On the body, in convenient relation to the pedal mechanism 18, is secured the occupant's seat 20, which latter also may be of conventional design.

Secured to the arms 13, 13, near their lower ends, are angle brackets 21, 21, respectively, and extending over a portion of the body 10 and diagonally downward and through said brackets is a rod 22 having nuts 23 threaded on its free ends bearing against the brackets whereby the arms 13, 13 may be sprung to move the shaft rearwardly with respect to the body to tighten the chain 19, and whereby a brace is provided to maintain the body rigid with respect to the shaft.

The front wheel 11 is disposed between a pair of spaced arms 24, 24 and is journaled on a shaft that connects said arms at their lower ends, said arms extending upwardly and preferably being inclined slightly towards the rear of the vehicle and at their upper ends being converged towards one another and having secured between them a downwardly extending lug 25 on a steering handle or wheel 26. Connecting said arms near their upper ends is a pair of relatively spaced cross members 27, 27 through which

are formed alined openings 28, and, likewise, connecting said arms at a lower point is another pair of relatively spaced cross members 29, 29 through which are formed 5 alined openings 30 that are alined also with the openings 28.

The end portions of a strap 31 are suitably bent to lie against and be secured to upper and lower portions of the body 10 at 10 the front thereof and at spaced points along the intermediate portion of said strap there is secured thereto a pair of U-shaped brackets 32 and 33, each of which includes a pair of forward extensions 34, spaced relatively 15 an amount equal to the spacement of the respective pairs of cross bars 27, 27 and 29, 29 and through which are formed alined openings 35.

The extensions 34 are adapted to be disposed over the cross bars 27, 27 and 29, 29, respectively, with the openings in said cross bars and extensions alined to receive pins or bolts 36 through the instrumentality of which the arms 24, 24 are pivotally connected to the body, so that by means of the steering handle or wheel 26, the said arms may be rotated to swing the front wheel 11 at different angles with respect to the direction of travel of the vehicle whereby the 30 latter may be steered.

The general construction of my improved toy as shown in the drawings and as described herein permits the use of a body of relatively thin, vertically disposed material, 35 and the specific manner of forming the connection between the body and the front wheel 11 permits the same connection to be used for body portions of different shapes, since the ends of the strap 31 may be bent 40 to fit practically any shape of body portion, as is indicated by the variance in the shape of the body portions of Figures 1 and 5.

I claim:

1. In a toy vehicle, a body portion, arms

secured at their upper ends to said body 45 portion and extending downwardly from the latter, a wheel shaft carried by said arms, propelling mechanism for said vehicle including a sprocket on said shaft, a sprocket on the body, a chain connecting said sprockets, and a combined chain tightener and body brace consisting of a rod adjustably secured at its ends to said arms and extending diagonally upward and over a portion 50 of said body.

2. In a toy vehicle, a body portion, arms secured at their upper ends to said body portion and extending downwardly from the latter, a wheel shaft carried by said arms, brackets secured to said arms near their 60 lower ends, propelling mechanism for said vehicle including a sprocket on said shaft, a sprocket on the body and a chain connecting said sprockets, a body brace extending over a portion of the body diagonally downward and through said brackets, and nuts threaded on the ends of said rod and bearing against said brackets whereby said rod may be placed in tension to spring the arms 65 rearwardly with respect to the body to 70 tighten said chain.

3. In a toy wheeled vehicle, a body portion, a strap the end portions of which are bendable to conform to the configuration of body portions of different shapes, spaced 75 lateral extensions on the intermediate portion of said strap, a pair of arms between which a wheel of the vehicle is journaled, cross members connecting said arms, and pintles engaged through said cross members 80 and said extensions to pivotally connect the arms with the body, so that the latter may be steered by turning said arms on said pintles.

In witness whereof, I have hereunto subscribed my name.

WM. F. DATHAN.
